CLAIM

The ornamental design for a poncho wrap, as shown and described.

DESCRIPTION

FIG. 1 is a front perspective view of a poncho wrap of Applicant's design;

FIG. 2 is a front view thereof;

FIG. 3 is a rear view thereof;

FIG. 4 is a right side elevational view thereof;

FIG. 5 is a left side elevational view thereof;

FIG. 6 is an upper elevational view thereof;

FIG. 7 is a lower elevational view thereof;

FIG. 8 is a front perspective view of the poncho wrap shown in FIGS. 1-7 as it might be worn by a user;

FIG. 9 is a rear perspective view of the poncho wrap shown in FIGS. 1-7 as it might be worn by a user;

FIG. 10 is a right side perspective view of the poncho wrap shown in FIGS. 1-7 as it might be worn by a user; and,

FIG. 11 is a left side perspective view of the poncho wrap shown in FIGS. 1-7 as it might be worn by a user.

The broken line outline of the partial human figure in FIGS. 8-11 assists in illustrating how the Poncho Wrap may appear when in a position of use, but forms no part of the claimed design.
